UNITED STATES PATENT OFFICE.

PATRICK JOSEPH CONWAY, OF KILMORE, VICTORIA, AUSTRALIA.

SHARPENING OR DRESSING MEANS FOR MACHINE-KNIVES AND THE LIKE.

1,117,552.

Specification of Letters Patent.

Patented Nov. 17, 1914.

Application filed April 22, 1914. Serial No. 833,771.

To all whom it may concern:

Be it known that I, PATRICK JOSEPH CONWAY, a subject of the King of Great Britain and Ireland, &c., residing at Kilmore, in the 5 State of Victoria, Commonwealth of Australia, have invented certain new and useful Improvements in Sharpening or Dressing Means for Machine-Knives and the like; and I do hereby declare the following to be a 10 full, clear, and exact description of the invention, such as will enable others skilled in the art to which it appertains to make and use the same.

The object of my invention is to provide 15 improved apparatus for sharpening knife blades used on wheels of chaff cutting machines and on other machinery. Sharpening by means of a hand file or stone is to a large extent still practised but is laborious, 20 slow and imperfect. My device is desirable by reason of its effectiveness, rapid action, and cheapness.

I use my device not only without taking 25 the knives from the carrying wheel, but also in many cases without moving the wheel from its machine. If I remove the wheel, leaving the knives on, the wheel will be temporarily held or supported as standing vertically or obliquely in some usual or suitable 30 manner. My device also promotes safety.

I use a lever, sharpening bit, lever socket, and other parts, and will now proceed to 35 explain my details, by reference to drawings herewith which show one form of my construction.

Figure 1 is a front view of part of a fitted chaffcutter knife wheel, only one of the 40 knives being shown. Fig. 2 is an end elevation, the wheel being in vertical section. Fig. 3 is a plan in horizontal section showing 45 some of the parts. Fig. 4 is an elevation, partly sectional, of some parts as seen from the back of Fig. 1. Fig. 5 is a plan in horizontal section as in Fig. 3, but showing parts at a lower level.

The parts are not in cutting positions in Figs. 1 and 2, and in these figures the scale is smaller than in Figs. 3 to 5. My sharpening bit is a removable two edged blade not 50 shown in Fig. 4.

a indicates the rim of a machine wheel which has knife blades b each suitably mounted as by bolting to some suitable spoke. The cutting edge, b¹, of the blade does not 55 form an arc of a circle in some cases, but

for any such divergence I make special provision. I can provide at will instead of a sharpener a polishing or dressing bit on my lever, but in this description will allude for brevity to the sharpener.

60

c in Fig. 1 is any suitable clamp, having means, as screw d or the like, to fix the clamp to the wheel at any convenient part, as to rim a.

e is a socket bearing arm extending from 65 the clamp with which it may be integral, and slotted longitudinally as at f, or likewise suited for the adjustment along it of a socket member h, extending from a swivel socket i which is adjusted to remain at a 70 desired point on the lower part g of a lever, having an upper part o, which is provided with adjustment and operating means, as one or more lateral handles p, p¹—and a top handle q. The lever may be in one or more 75 pieces, but as shown it has two main parts, o and g, connected as by a transverse part o¹ which may be on the former, and have a slot 80 o⁵, through which passes the top k (of reduced diameter) of part g. The top is fixed 85 in any desired adjustment as by the nut k¹. Part g has a collar g¹ which is further mentioned later. It carries a roller m which acts as an anti-friction member, and also as a rear support during the sharpening action. 90

h¹ represents a wing nut by tightening which the shank of socket i is fixed in some desired adjustment along arm e, without preventing the swiveling action of the socket. The latter action permits of radial 95 movement of the lever, and that movement permits my sharpening bit n to be swung to and fro in contact with the knife edge b¹. The radial movements are indicated by arrows in Fig. 1.

I provide a depression limiting adjustable stop j on part g by which to prevent undue lowering of the lever, which during the sharpening will be raised and lowered as may be required according to the position 100 of edge b¹ so as to bring the sharpening bit n to the right height, while the lever is moved to and fro as per arrows in Fig. 1. During part of the movement the stop j can rest on arm e; and there is the additional advantage that the stop prevents the transverse part o¹ of the lever being lowered so far as to injure the blade edge b¹.

g¹ is a supporting collar or the like on part g, and m¹ are distance pieces or wash- 110

ers used so that roller m may be suitably located relatively to one side of blade b .

The various handles may be adjusted in height. Thus handle p (or handles p , p^1) 5 engages a slot o^2 in lever o .

o^3 are flanges on lever o between which is set a sharpening bit n , the base of which is concave as at n^4 with cutting edges n^1 as in Fig. 5, so that the sharpening action can 10 proceed in whichever radial direction the lever is swung. To enable adjustment of the bit n higher or lower, and to fix it to the lever, the latter has a slot o^4 , taking a bolt n^2 , held by a nut n^3 . The bolt head 15 may be set in flush or nearly so by recessing, the slot o^4 at o^6 Fig. 4.

The operator may take parts p and q in respective hands, or parts p , p^1 . Then after 20 carefully adjusting the pivotal socket i in what he thinks the most serviceable position, he will rotate the lever on its axis slightly until the positions of roller or the like m , bit n and edges n^1 are as in Figs. 3 and 5. Then the radial action follows as 25 per arrows in Fig. 1, accompanied by such rising and lowering and axial rotation to and fro of the lever as the operator finds advisable to keep the bit at work. The fact of roller m contacting with one side of blade 30 b enables the worker to exert pressure on the blade with the bit edge and so shave down the edge b^1 readily. If the cutting action is to stop, a slight rotation or twist of the lever 35 reversely to the arrows in Figs. 3 and 5 will suffice.

Bits n may be formed of different shapes and styles generally, and one may be changed for another.

Various modifications of minor detail 40 may be used without departing from what I claim. Thus framing could take the place of arm e .

The operator can vary the pressure on edge n^1 so as to make it light or heavy at 45 will when drawing that edge along edge b^1 .

Having now fully described and ascertained my said invention, and the manner in

which it is to be performed, I declare that what I claim is:—

1. A sharpening or dressing device for 50 blades on machine wheels, comprising in combination, a lever, adjustable means adapted to be secured to the wheel for supporting said lever at its lower end and adapted to allow a rising and falling movement of the same, and also an oscillatory movement, handles on said lever at its upper end whereby said lever may be normally moved, and a bit adapted to act on said blade during the oscillatory and rising and 55 falling movements.

2. A sharpening or dressing device for 60 blades on machine wheels, comprising a wheel clamp, having an arm, means for the adjustment on the arm of a socket or pivot, 65 a lever to engage the socket and having handles by which to lift and lower, partially rotate, and draw to and fro the said lever, a roller or member on the lever to bear on one side of a wheel blade, and a bit or sharpener on the lever to bear on the other side of the blade as described.

3. In a device of the kind indicated, a 70 raisable lever, a stop to limit its descent, an adjustable support allowing partial rotation of the lever on its axis, an adjustable bit, and a member to meet the blade to be treated on the other side from the bit when the latter is acting on the blade.

4. In a device of the kind indicated, a 75 lever formed of an upper and a lower member, a transverse slotted part on one member, allowing of adjustable connection of the said members, the upper member carrying a bit, and the lower member a roller or 80 like contact piece, the lever being supported to allow it to be given sharpening motion as described.

In witness whereof I have hereunto set 85 my hand in the presence of two witnesses. 90

PATRICK JOSEPH CONWAY.
